UNITED STATES PATENT OFFICE.

ALBERT J. PERKS, OF SPRINGFIELD, OHIO, ASSIGNOR TO WEBSTER AND PERKS TOOL COMPANY, OF SPRINGFIELD, OHIO, A COPARTNERSHIP.

STRAIGHT-EDGE.

No. 905,357.

Specification of Letters Patent.

Patented Dec. 1, 1908.

Application filed March 23, 1907. Serial No. 364,056.

To all whom it may concern:

Be it known that I, ALBERT J. PERKS, a citizen of the United States, residing at Springfield, in the county of Clark and State 5 of Ohio, have invented certain new and useful Improvements in Straight-Edges, of which the following is a specification, reference being had therein to the accompanying drawings.

10 The present invention relates to straight-edges of the character employed by paper-hangers.

15 The object of the invention is to provide such a straight-edge with reinforcing means adapted to prevent the same from warping or twisting, and further, to provide the straight-edge with sufficient weight to cause the same to rest firmly upon the paper and prevent its slipping or creeping thereon.

20 With these objects in view my invention consists of certain novel features of construction to be hereinafter described, and then more fully pointed out in the claim.

25 In the accompanying drawings, Figure 1 is a perspective view of a section of a straight-edge embodying my invention; and Fig. 2 is a transverse, sectional view of the same.

30 In these drawings, I have illustrated my invention as embodied in an ordinary straight-edge of the type usually employed by paperhangers and comprising a body portion 1, provided on one edge with a metal binding strip 2 and on its other edge with a 35 guide strip 3 having its upper portion turned at right angles thereto, as shown at 4, and extending over a portion of the groove 5, thus forming a guide or track upon which the trimmer travels. The body portion 40 of such a straight-edge is usually made of wood and is very liable to warp or twist and become worthless. To overcome this tendency I provide the straight-edge with a strip of metal 6 which is preferably secured 45 to the upper face of the straight-edge in any suitable manner, as by the screws 7. This strip may be of sufficient strength to hold

the wooden body portion against warping and of sufficient weight to cause the straight-edge to lie firmly upon the paper and reduce 50 the liability of the same to slip or creep thereon. But, if desired, a second strip 8 may be mounted in a groove or recess 9, formed in the bottom of the body portion and extending preferably for the full length 55 thereof. This strip may be secured within the groove 9 in any suitable manner, as by the screws 10. This second strip adds both to the strength of the straight-edge to resist the tendency to warp and to the weight 60 thereof to further prevent creeping. Thus, it will be seen that I have provided a straight-edge, the wooden body portion of which is provided with one or more metal reinforcing strips extending for substantially 65 the full length of the straight-edge and rendering the same rigid so as to prevent warping, and further, so increasing the weight of the straight-edge as to cause the same to firmly engage the paper and prevent 70 the same from slipping thereon.

I wish it to be understood that I do not desire to be limited to the exact details of construction shown and described, for obvious modifications will occur to a person 75 skilled in the art.

Having thus fully described my invention, what I claim as new and desire to secure by Letters Patent, is:—

80 A straight-edge for paper cutters comprising two metallic strips, one above the other, a wooden body portion grooved on the bottom to receive one of said strips and supporting the other metallic strip on its upper face, whereby the wooden portion is both 85 weighted and reinforced, and means formed in and carried by the wooden portion, independent of said strips, to guide the cutter.

In testimony whereof, I affix my signature in presence of two witnesses.

ALBERT J. PERKS.
